UNITED STATES PATENT OFFICE.

FAGGIO MARTINO, OF PERRIS, CALIFORNIA.

HEEL FOR BOOTS AND SHOES AND THE LIKE.

Application filed January 15, 1925. Serial No. 2,543.

To all whom it may concern:

Be it known that I, FAGGIO MARTINO, a subject of the King of Italy, residing at Perris, in the county of Riverside and State of California, have invented a new and useful Heel for Boots and Shoes and the like, of which the following is a specification.

My invention is an improved shoe heel of the type formed of a resilient material such as rubber.

An object of my invention is to provide a novel means whereby a heel of the character set forth may be securely fastened to or retained on the heel.

Another object is to provide novel means whereby the nails which are used to secure the heel to a boot, shoe or the like will not be likely to be torn out of the heel and thereby release the heel.

I accomplish this by embedding a quilted layer of laminated material within the heel, through which the shank of the nails are driven, but through which the heads of said nails cannot pass.

In constructing my heel, I place therein sheets of canvas stitched together. This quilted fibrous layer is positioned above the lower or wearing surface of the heel so as not to be visible, and openings are provided in the heel to the depth of the layer so that the nails may be inserted therein and driven through the quilted fibrous layer and the heel.

Another object is to provide a nail head retaining means, for rubber heels and which means will not separate from the heel, and work out.

My invention is broadly new, basic and pioneer in that I am the first to embed a quilted laminated strip of fabric in a rubber heel and which connects all of the securing nails and prevents the heads thereof from tearing out of the material.

Other objects, advantages and features of invention may appear from the accompanying drawing, the subjoined detailed description and the appended claims.

The accompanying drawing illustrates the invention applied to heels of various forms.

Figure 1 is a longitudinal sectional view of a heel embodying my invention as applied to a man's shoe, a portion of which is shown in section.

Fig. 2 is a sectional view taken on line α^2 , Fig. 1.

Fig. 3 is a longitudinal sectional view of a heel embodying my invention as applied to a woman's shoe a fragment of which is shown.

Fig. 4 is a sectional view taken on line α^4 , Fig. 3.

Fig. 5 is a diagrammatic view of a fibrous strip of quilted canvas forming my retaining means, and illustrating how the heel layers are cut therefrom with a minimum of waste.

The numeral 1 indicates a heel preferably formed of a resilient material such as rubber, and which is secured to a shoe α as will be further described.

In molding the heel 1 a quilted layer of fibrous laminated material 2 is placed therein, and the rubber molded around it. The rubber will mold itself closely about the fibrous layer so as to make the layer practically an integral part of the completed heel, thus removing any possibility of said layer breaking away from and working out of the heel.

A plurality of holes or recesses 3 extend from the lower or wearing surface b of the heel 1 to the quilted layer 2. This enables the nails 4 to be started directly through the fibrous layer and hence through the rubber heel and into the shoe.

The head of the nail is driven, by means of any suitable instrument well-known in the trade, flush with that surface of the fibrous layer 2 through which the nail first enters.

The outer periphery of the quilted layer 2 is also slightly smaller than that of the heel 1 so that the edges of the layer 2 will not protrude and make an unsightly appearance.

I have here illustrated the fibrous strip 2 as composed of a quilted layer 5 of canvas, which is folded upon itself or a predetermined number of layers are superimposed and then secured together by stitches 6 to form a composite piece.

A further advantage of having a laminated fibrous strip is that the fibers in the various layers will extend in different directions, and thus offer a greater resistance to the passage of the head of the nail therethrough and prevent accidental dislodgement of the usual securing nails 4.

Advantages gained in using a quilted laminated strip of material instead of metal

washers or other devices heretofore suggested to prevent the nail heads from passing through the rubber heel are ease of manufacture and that when the rubber is 5 worn down to expose the securing means my quilted fabric strip will present a resilient and durable-wearing surface to the sidewalk instead of the metal washer or easily worn out material, thus making for 10 greater comfort to the wearer.

I claim.

1. In a resilient shoe heel, a fibrous resilient quilted layer of canvas mounted therein as and for the purpose set forth.
- 15 2. A layer comprising a plurality of sheets

of canvas stitched together for strengthening a shoe heel of resilient material.

3. A shoe heel comprising a rubber body and a quilted layer adapted to form a wearing surface consisting of strips of canvas 20 stitched together and positioned above the lower surface of the rubber body and said body having holes extending from the wearing surface thereof to said quilted layer to accommodate nails to be driven through the 25 layer to secure it to a shoe.

In testimony whereof, I have hereunto set my hand at Perris, California, this 7th day of January, 1925.

FAGGIO MARTINO.
